UNITED STATES PATENT OFFICE.

ALBERT E. LYITLE, OF CHICAGO, ILLINOIS, ASSIGNOR OF ONE-HALF TO H. F. DOUSMAN, OF CHICAGO, ILLINOIS.

WASTE-PIPE STRAINER.

SPECIFICATION forming part of Letters Patent No. 738,726, dated September 8, 1903.

Application filed December 28, 1902. Serial No. 136,612. (No model.)

To all whom it may concern:

Be it known that I, ALBERT E. LYITLE, a citizen of the United States, residing at Chicago, in the county of Cook and State of Illinois, have invented certain new and useful Improvements in Strainers for Waste-Pipes, of which the following is a specification.

This invention relates to improvements in a strainer to be used in connection with the waste-pipes of sinks and other basins; and it consists in certain peculiarities of the construction, novel arrangement, and operation of its parts, as will be hereinafter more fully set forth and specifically claimed.

15 The principal object of my invention is to provide a strainer which shall be of such construction that it will permit of the free escape of water from the sink or other vessel, yet will prevent the accumulation of bits of 20 papers, toothpicks, burned matches, coffee-grounds, and other articles which are usually thrown in the sink or basin from clogging or closing the mouth of the outlet or escape pipe, thereby causing the sink or vessel to overflow, as is usually the case when the strainers heretofore in use have been employed.

Other objects and advantages of the invention will be disclosed in the subjoined description and explanation.

30 In order to enable others skilled in the art to which my invention pertains to make and use the same, I will now proceed to describe it, referring to the accompanying drawings, in which—

35 Figure 1 is a perspective view of a portion of a sink and a part of the waste-pipe thereof, showing my improved strainer in position. Fig. 2 is an enlarged central sectional view through the strainer and a portion of the bottom of the sink or vessel. Fig. 3 is a plan view showing a modified form of the strainer, and Fig. 4 is a view in side elevation of another modification thereof.

Similar letters refer to like parts throughout 45 the different views of the drawings.

A represents a portion of a sink, which may be of the ordinary or any preferred construction and, as usual, is provided with a screw-threaded opening α , in which the waste-pipe

B is secured. Surrounding the opening α and on its lower surface the bottom of the sink or vessel A is provided with a screw-threaded neck b to engage the waste-pipe and a lock-nut b' , used to more securely hold the waste-pipe in position. The upper surface 55 of the bottom of the sink or vessel A is usually formed with a recess a' around the opening α to receive the ordinary perforated and flat strainer-plate, which, as is well known, is secured in place by means of screws, 60 which soon become corroded and rusted to such an extent that they cannot be removed when it is desired to remove said plate. It is therefore one of the objects of my invention to provide a strainer which can be easily detached to permit of it being cleaned, but when in position for use will be firmly held against accidental dislocation. The strainer consists of a balloon or pear shaped body C, having a series of perforations c and at its lower portion 70 a number of upwardly-extending slots c' , which preferably taper toward their upper ends. The tapered lower portion of the body C is provided with an annular flange c^2 , which rests in the recess a' , from which the ordinary strainer-plate has been removed, so as to be flush with the upper surface of the bottom of the sink. The lower surface of the flange c^2 is provided with a neck c^3 , of any suitable length, to fit within the upper portion 75 of the waste-pipe B, thus further securing the strainer in place and so as to prevent it tipping over. As shown in Fig. 2 of the drawings, the neck c^3 surrounds the opening c^4 in the lower end of the strainer-body. In 80 Fig. 3 of the drawings I have shown a modified form of the strainer, which consists in making it of two pieces C' and C^2 instead of one piece, as shown in Figs. 1 and 2 of the drawings. Each of the pieces C' and C^2 is 85 provided at each of its sides with lugs d , through which are passed screws or rivets d' , used to hold the pieces comprising the strainer together. For the convenience of manufacture I prefer to make the strainer of 90 two pieces, but do not desire to be limited to such a construction. In Fig. 4 of the drawings is shown still another modification, which

consists in omitting the flange c^2 and also the perforations c , yet employing the upwardly-extending slots c' and neck c^3 to fit in the upper end of the drain-pipe or opening in the bottom of the basin or vessel.

From the foregoing and by reference to the drawings it will be seen and clearly understood that by using a strainer embodying my invention the water will be allowed to escape at all times, and as it passes through the slots c' the accumulations of the bits of paper, coffee-grounds, and the like will be caused to settle around the lower portion of the body by reason of its inwardly-tapered shape, thus preventing the openings becoming clogged, so as to cause overflow of the basin or vessel. It is also apparent that the strainer may be readily removed when it is desired to clean the same and easily replaced.

Having thus fully described my invention,

what I claim as new, and desire to secure by Letters Patent, is—

1. As an improved article of manufacture, a strainer comprising a perforated body portion tapered toward its lower part and provided at its lower portion with an annular flange having on its lower surface a neck communicating with the body portion, substantially as described.
2. As an improved article of manufacture, a strainer comprising a body portion contracted at its lower part, and having a series of openings and a number of upwardly-extending slots, an annular flange on its lower portion, and a neck on the lower surface of said flange, substantially as described.

ALBERT E. LYTHE.
